UNITED STATES PATENT OFFICE.

THOMAS F. DEPUY, OF MAUCH CHUNK, PENNSYLVANIA, ASSIGNOR TO LEHIGH STOVE AND MANUFACTURING COMPANY, OF LEHIGHTON, PENNSYLVANIA, A CORPORATION OF PENNSYLVANIA.

AIR-PREHEATING MEANS FOR SOLID-FUEL-BURNING STOVES.

Application filed April 18, 1922. Serial No. 555,163.

To all whom it may concern:

Be it known that I, THOMAS F. DEPUY, a citizen of the United States, and a resident of Mauch Chunk, in the county of Carbon 5 and State of Pennsylvania, have invented an Improvement in Air-Preheating Means for Solid-Fuel-Burning Stoves, of which the following is a specification.

In the case of solid fuel burning stoves 10 of certain types and kinds, for instance, cooking stoves, it is desirable that means be provided for causing relatively quick ignition of the fuel at certain points or within certain regions adjacent some part or compartment of the stove which should be quickly heated.

The object broadly of my invention is to provide means whereby portions of the fuel at certain selected points or within a selected predetermined region may be more quickly ignited than would be the case if the device embodying my invention were not present.

A more specific object of my invention is 25 to provide means whereby air may be cheaply and economically pre-heated and admitted to the said selected predetermined region within the fire box.

A further general object of the invention 30 is to provide a device of the character indicated which is simple in construction and which may be cheaply and economically manufactured and placed in use.

In order that the invention may be readily 35 understood and its practical advantages fully appreciated, reference should be had to the accompanying drawing in which I have illustrated one form of embodiment of the device embodying the said invention; 40 but it will be understood that the invention is susceptible of embodiment in forms of construction other than that shown and that changes in the details of construction may be made within the scope of the claims 45 without departing therefrom.

In the drawing:

Fig. 1 is a vertical sectional view of a portion 50 of a stove provided with the device or means embodying my invention which view is taken in a plane parallel with the front of the said stove;

Fig. 2 is a view in side elevation of the 55 said device looking toward the right in Fig. 1;

Fig. 3 is a view in side elevation of the 55 said device looking toward the left in Fig. 1; and

Fig. 4 is a horizontal sectional view of the 60 said device taken on the line 4—4 of Fig. 1.

It will be noticed that I have shown my 65 invention as applied to or embodied in a cook stove, but it will be understood that it may be applied to other kinds of stoves should such application become desirable.

Referring to the drawings: 1 designates 70 the fire box of a solid fuel burning stove and 2 the fuel therein. The grate for supporting the fuel is not shown. At one side of the fire box a water holding and heating receptacle 3 is shown by means of which a supply of heated water may be provided. The said water heating receptacle 3 is supported against an outer wall structure 4 of the stove. The air for effecting and controlling combustion of the fuel 2 is supplied through a controllable draught opening 5 in the side of the stove. The heated gases emitted from the fire box or combustion chamber travel therefrom upwardly and laterally through a passageway 7 and 75 thence around the oven 8 in known manner.

The device embodying my invention is 80 situated intermediate the fire box or chamber 1 and the wall 10 of the oven 8 adjacent the fire box or combustion chamber 85 and is secured to said wall by a bolt 10^a. The said device constitutes the lower part of the side of the fire box or chamber adjacent said oven. The said device comprises a box-like member having a bottom 90 11, upper and lower sides 12 and 13 and end walls 14. The outer or top edges of the upper and lower sides 12 and 13 and the end walls 14 contact with the adjacent wall 10 of the oven 8 to form an air chamber, 95 as clearly shown in Fig. 1. The lower side 13 of the device is provided with a downwardly extending portion 15 terminated at its opposite ends in outwardly extending projections 16. These projections extend 100 underneath a shoulder 17 formed in the wall 10 of the oven 8 and the outer edges thereof contact with the bottom of an inwardly depressed portion of said wall so as to form a channel 18 leading from the 105 ash pit chamber below the fire box into the said air chamber.

A portion of the bottom 11 of the said

device a distance above the upper edge thereof extends inwardly toward the wall 10 as indicated at 20 so as to form a shoulder 21 which extends lengthwise of the said device and in parallel relation to the top side wall 12 thereof. The said shoulder is provided with openings 22 at intervals therein through which the air is adapted to flow from the chamber within the said device 10 into the fire box or chamber. The direction of flow is indicated by the arrows 23 in Fig. 1. The bottom 11 of the said device is situated in direct contact with the lower inside portion of the burning fuel 2 within 15 the fire box or chamber 1 and in consequence is quickly heated so that the air which enters the air chamber is pre-heated.

The top side 12 of the pre-heating device constitutes a support for the insulating lining 25 situated intermediate the fire box or chamber 1 and the upper portion of the side wall 10 of the oven 8. This lining, in the construction shown, consists of firebrick. The lower edge of this lining is retained 25 in position by means of the shoulder or flange-like portion 26 which projects upwardly in the plane of the bottom 11 of the pre-heating device, as clearly shown in Fig. 1 of the drawing.

Assuming that a fire has been started within the fire box or chamber, the bottom portion of the coal is first ignited. The hot gases flow or travel upwardly through the bed of coal or other solid fuel and ultimately the entire bed becomes ignited. Without the presence of a device such as that constituting my invention disclosed herein the entire bed of solid fuel would become ignited progressively from the bottom upwardly, but it is desirable that the portion of fuel adjacent the oven should be ignited more quickly than usually is the case in order that the oven may become more quickly heated. It is for the purpose 45 of accomplishing this result that my invention has been provided. As already indicated, the bottom portion of the fuel is first ignited, consequently the device constituting my invention and which co-operates with the adjacent inner wall of the oven to form a pre-heating air chamber becomes quickly heated so that the air entering the said chamber through the channel 18 is likewise quickly heated and in its heated state is delivered through the openings 22 into fuel 2 in the fire box or chamber 1 at a point a considerable distance above the bottom thereof. The said pre-heated air flows upwardly through the fuel 50 adjacent the fire-brick 25 and, by reason of having been pre-heated, is quickly ignited. It follows that the fuel within the region adjacent the oven above the point of delivery of the pre-heated air into the fire box or chamber is quickly ignited so

that the oven is more quickly heated than would be the case if the device embodying my invention were not employed. By this means a substantial economy in time may be effected as well as a more satisfactory 70 combustion of the fuel.

Having thus described my invention what I claim and desire to secure by Letters Patent is:

1. A solid fuel burning stove comprising 75 a fuel chamber, the lower portion of the side of which adjacent the oven chamber consists of a box-like member, the bottom of which faces the fuel chamber and the sides and ends of which extend toward the said oven chamber, means for detachably securing the said box-like member to said oven chamber with the edges of said member in contact with a side wall of said oven chamber, the lower side wall of said box-like member being provided with an opening through which air is adapted to enter the chamber formed between the said box-like member and the adjacent wall of the said oven chamber, and the bottom of said box-like member being provided with openings through which pre-heated air is adapted to be discharged from the chamber formed by the said box-like member and the adjacent side wall of the said oven chamber into the 85 fuel chamber at a point a distance above the bottom of the fuel chamber below the normal top level of the bed of fuel therein. 90

2. A solid fuel burning stove comprising a device of box-shape having bottom, side and end walls, the edges of which are adapted to contact with the outer side of the inner wall of a chamber to be heated, the lower side of the said device having outwardly and downwardly extending projections to form a 105 channel through which air is adapted to enter the chamber within said device and a portion of the bottom of said device a distance above the lower edge thereof being extended inwardly to form a shoulder which 110 extends in parallel spaced relation with respect to the upper side of said device and the said shoulder being provided with openings therethrough for the passage of air from the chamber within said device into the 115 fire box or chamber.

3. A solid fuel burning stove comprising an open box-shaped device, means for securing the said device to a wall of the said stove with its edges seated against said wall 120 to form a closed chamber within the said device, the said device constituting the lower portion of one of the side walls of the fire box of said stove, and the lower side of said device being provided with depending and 125 outwardly extending projections to form a channel for the passage of air into the chamber within the said device and the bottom of the said device a distance above its lower edge being extended inwardly to form a 130

shoulder having openings therein which openings open downwardly for the passage of pre-heated air from the said chamber into the fire box, substantially as and for the 5 purpose described.

4. In a solid fuel burning stove comprising an oven and a fire box, the combination of an open box-like member, the edges of which contact with the outer side of the 10 wall of the said oven which is adjacent the fire box, means for securing the said device to and holding it against the said wall, the lower side of the said device being provided with inwardly and downwardly extending 15 projections to form a channel for the admis-

sion of air into the chamber within the said device and the bottom of the said device a distance above its lower edge extending inwardly to form a shoulder in spaced relation to the upper side of said device which 20 shoulder is provided with openings extending therethrough, an insulating lining supported upon the upper side of said device and situated between the combustion chamber and the adjacent wall of the said 25 oven, substantially as described.

In testimony that I claim the foregoing as my invention I have hereunto signed my name this 17 day of April, 1922.

THOS. F. DEPUY.
